UNITED STATES PATENT OFFICE.

HARRY N. LAPLANT, OF DETROIT, MICHIGAN.

CRUTCH.

1,322,800.

Specification of Letters Patent. Patented Nov. 25, 1919.

Application filed March 6, 1919. Serial No. 280,952.

To all whom it may concern:

Be it known that I, HARRY N. LAPLANT, a citizen of the United States, residing at Detroit, in the county of Wayne and State 5 of Michigan, have invented certain new and useful Improvements in Crutches, of which the following is a specification.

This invention is a crutch and has for its principal object the production of a yielding 10 shoulder support, whereby shocks will be absorbed by this support to relieve jar- ring from the shoulder of the user.

Another object of this invention is the production of a crutch wherein the shoulder support is formed from a strip of resilient material, having the end portions thereof 15 bent to provide a plurality of convolutions which are retained upon the cross piece of the crutch whereby the user may use the 20 crutch without the jar being imparted to his shoulder, since the shoulder support will yield to absorb shocks when undue strain bears thereupon.

One practical form of construction and 25 assembly of the present invention will be hereinafter described and is illustrated in the drawing, in which

Figure 1 is a side elevation of the shoulder support, the crutch member being shown in 30 fragmentary elevation.

Fig. 2 is an enlarged fragmentary sectional view through a portion of the device illustrating the manner in which the retaining 35 frames are used.

Fig. 3 is a fragmentary sectional view taken on the line 3—3 of Fig. 2.

In the preferred embodiment of the present invention, about to be described, 5 designates the supporting standards of the usual 40 construction having the horizontally extending cross piece 6 fixed upon their upper ends in the usual manner.

This construction may be of any desired 45 nature, as the invention resides in the specific construction of the shoulder support and the retaining means therefor, the particular illustration of the crutch member herein made being for the purpose of disclosing the operation of the specific invention.

The shoulder support is formed from a single strip of material and comprises a longitudinally curved body 7, the central portions of the body being the lowest, while 55 the body extends upwardly adjacent its outer ends, thus providing a socket like por-

tion to permit the shoulder support from slipping from the arm pit of the user when the device is in use.

The body 7 of the shoulder support has 60 semi-circularly curved end portions 8 from which extend the converging fingers 9 as shown in Fig. 1. The fingers extend downwardly and terminate in a plurality of spaced convolutions 10 which are of a spring 65 like construction, since the shoulder support is preferably formed of resilient material. It will be noted that the convolutions 10 are formed of the lower ends of the fingers 9.

Retaining frames 11 are provided, it being noted that these retaining frames are substantially of an inverted U-shaped construction as shown in Fig. 3. The body portions of these retaining frames have flat inner surfaces, although the outer surfaces 75 thereof are rounded to eliminate uneven edges. The shanks 12 extend from the sides of each retaining frame, the lower ends of the shanks 12 being threaded as shown at 12'.

As will be noted in Fig. 1, the shoulder 80 support is provided with convolutions upon each finger 9 and a retaining frame 11 is passed through each series of convolutions. Reinforcing plates 13 are carried upon the upper surfaces of the cross piece 6 and it 85 will be noted that the lower ends of the sides of the retaining frames 11 bear upon these plates 13, although the shanks 12 extend through these plates and also pass through the cross piece 6 as shown in Fig. 3. 90

A binding plate 14 is carried upon the projecting ends of each pair of shanks and nuts 15 are then screwed onto these shanks to firmly clamp the plates upon the cross piece and also hold the retaining frames in 95 set position.

By referring particularly to Fig. 1, it will be noted that the convolutions of the fingers are coiled in opposite directions and for this reason when the frames are fixed upon the 100 cross piece 6 and are engaging the convolutions, the shoulder piece will be firmly held from displacement. However, the convolutions 10 loosely pass through the frames, as shown in Figs. 2 and 3, thus allowing the 105 convolutions to expand or contract freely, although being held from displacement by the frames.

When the device is in use, the crutch is used in the usual manner and at this time 110 the shoulder support is positioned under the armpit of the user or directly below the

shoulder. As considerable pressure is applied to the shoulder piece, under various conditions, it is obvious the resilient construction thereof will cause the body 7 to spring downwardly a slight distance, while the fingers 9 will also spring or yield, as will the convolutions 10, thus allowing undue shocks to be absorbed by the shoulder support, without jarring the shoulder of the user or otherwise rendering use of the crutch uncomfortable.

From the foregoing description it will be seen that a very simple shoulder support has been produced, which is of a resilient construction, thus allowing the same to be easily held in engagement with the armpit of the user, although the shoulder support will easily yield to constitute a shock absorber, while the frames will permit of the expansion and contraction of the shoulder support, although firmly holding the same in position upon the cross piece of the crutch element.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. In a device of the character described, the combination of a crutch element, a resilient shoulder support formed from a single strip of material and comprising a longitudinally curved body, end portions of said body being curved substantially semi-circularly and terminating in downwardly extending converging fingers, said fingers terminating in oppositely coiled spaced convolutions, and means holding the convo-

lutions upon the crutch element, thus holding the shoulder support from displacement.

2. In a device of the character described, the combination of a crutch element, a shoulder support formed from a strip of resilient material and comprising a body having oppositely curved ends, downwardly extending converging fingers projecting from the ends and terminating in oppositely coiled spaced convolutions, substantially inverted U-shaped retaining frames passing through said convolutions and being fixed upon said element, thus holding said shoulder support in a desired position, although allowing the same to easily yield when pressure is brought to bear thereon.

3. In a device of the character described, the combination of a crutch element, a resilient shoulder support formed from a single strip of material and comprising an elongated body, the end portions of said body being coiled into a plurality of convolutions which rest upon the crutch element, and means for holding the convolutions against displacement, thus holding the shoulder support in position for use.

4. In a device of the character described, the combination of a crutch element, a shoulder support formed from a strip of resilient material and comprising an elongated body, the end portions of said body being coiled to form a plurality of convolutions, substantially inverted U-shaped retaining frames passing through said convolutions and being fixed upon said element, thus holding said shoulder support in a desired position, although allowing the same to easily yield when pressure is brought to bear thereon.

In testimony whereof I affix my signature in presence of two witnesses.

HARRY N. LAPLANT.
